DESIGN FOR A FINGER RING

Abraham Sager, Chicago, Ill.

Application August 2, 1935, Serial No. 57,915

Term of patent 14 years

To all whom it may concern:

Be it known that I, Abraham Sager, a citizen of the United States and resident of Chicago, in the county of Cook and State of Illinois, have invented a new, original, and ornamental Design for a Finger Ring, of which the following is a specification, reference being had to the accompanying drawing, forming a part thereof.

In the drawing, Fig. 1 is a perspective of the ring embodying my new design;

Fig. 2 is a face view of the front of the ring shown in Fig. 1; and

Fig. 3 is a plan view thereof.

I claim:

The ornamental design for a finger ring, as shown.

ABRAHAM SAGER.
